UNITED STATES PATENT OFFICE.

RAYMOND P. NORTON, OF MARSHALLTOWN, IOWA, ASSIGNOR OF ONE-THIRD TO W. A. NORTON, OF MARSHALLTOWN, IOWA.

CARBURETER.

1,135,544.

Specification of Letters Patent. Patented Apr. 13, 1915.

Application filed July 22, 1912. Serial No. 711,013.

To all whom it may concern:

Be it known that I, RAYMOND P. NORTON, a citizen of the United States, residing at Marshalltown, in the county of Marshall 5 and State of Iowa, have invented a certain new and useful Carbureter, of which the following is a specification.

The object of my invention is to provide a carbureter of simple, durable and inexpensive construction, provided with mechanism whereby the air inlet openings and the throttle valve to the engine may be controlled by a single lever.

A further object is to provide such a carbureter provided with means for adjusting the size of the air inlet opening with relation to the size of the discharge opening at the point where the throttle valve is located.

20 A further object is to provide the said carbureter having means whereby gasoline may be admitted to the mixing chamber by the operation of the same lever which controls the throttle valve, and the air inlet opening.

25 A further object is to provide in such a carbureter a simple and easily regulated means for adjusting the mechanism which controls the flow of gasoline into the mixing chamber.

30 A further object is to provide in such carbureter a new and novel adjustable device for regulating the size of the air inlet opening.

35 Still a further object is to provide a carbureter having mechanism for controlling the opening in the carbureter shell around the gasoline feed nozzle, and for controlling a valve which coacts with said nozzle in unison in such manner that air is permitted 40 to flow upwardly through the carbureter around the gasoline feed nozzle for producing a uniform mixture.

45 My invention consists in certain details, in the construction, arrangement and combination of the various parts of the device, whereby the objects contemplated are attained, as hereinafter more fully set forth, pointed out in my claims and illustrated in 50 the accompanying drawings in which—

Figure 1 shows a side elevation of the carbureter embodying my invention. Fig. 2 shows a vertical, central, sectional view of the same. Fig. 3 shows a vertical, central,

55 sectional view of the mixing chamber and adjacent parts taken on a line at right angles to the view shown of Fig. 2. Fig. 4 shows a top or plan view of my carbureter. Fig. 5 shows a top or plan view of the movable segmental plates whereby the air inlet 60 opening is formed. Fig. 6 shows a plan view of the circular plate just above the segmental plates shown in Fig. 5. Fig. 7 shows a detail view of part of the plate shown in Fig. 6, and of the link attached 65 thereto, and Fig. 8 shows a detail view of part of the actuating levers for operating the carbureter.

In the accompanying drawings, I have used the reference numeral 10 to indicate 70 generally the casings containing a float feed. Screwed into the bottom of the casing 10 and communicating with the interior thereof, is a gasoline inlet tube 11, the upper end of which forms a valve seat for the needle 75 valve 12. The upper end 13 of the casing 10 is a detachable plate and is provided with a central opening in which is received an externally and internally screwthreaded cylinder 14. Formed on the lower end of 80 the cylinder 14, within the casing 10 are opposite parallel downwardly extending bracket arms 15. Received in the upper end of the cylinder 14, is a screw plug 16, provided with a central, vertical, longitudinal 85 opening.

Extending upwardly from the valve 12 and slidably mounted in the screw plug 16, is a valve stem 17. In the lower part of the interior of the casing 10 is a circular 90 hollow float 18. On the stem 17 above the level of the float 18 is detachably mounted a collar 19. On the stem 17 between the collar 19 and the screw plug 16, is an extensible coil spring 20, designed to exert 95 yielding pressure to hold the valve 12 in its seated position.

In order to control the valve 12, and the position of the float 18, I secure to the upper side of the float 18, on opposite sides thereof, bell crank levers 21. One arm of each bell crank lever 21 is pivoted to the upper surface of the float 18, and is also so mounted thereon, as to permit a slight horizontal sliding movement of the end of the lever 100 with relation to the float. The other arm rests just below the collar 19. Each of the bell crank levers 21 is centrally pivoted on 105

one of the bracket arms 15, so that when the float is at the lower limit of its movement, its weight acting against the spring 20, will raise the valve 12.

5 When sufficient gasoline has been admitted to the interior of the casing 10 to raise the float 18, the inner ends of the bell crank levers 21 will be lowered and the spring 20 will force the valve 12 to its 10 seated position.

Formed on the lower portion of the casing 10 is a laterally extending casting 23. The casting 23 extends into and through a hollow cylinder 24. Within the cylinder 24 15 and extending upwardly therein, from the casting 23, is a tube 25. Formed in the casting 23, is a passage way 26, which leads from the lower portion of the interior of the casing 10, to the lower end of the tube 25. Extending downwardly from the passage 26 within the cylinder 24 is a short tube 27, in the lower end of which is a pet-cock 28, for draining the passage way 26 and the tube 25.

25 Approximately at the level of the upper end of the tube 25, the cylinder 24 is provided with a circumferential annular flange 29, which terminates in a vertical circumferential annular flange 30, which is externally screwthreaded. Above the cylinder 24, is a cylinder 31, somewhat smaller in diameter than the cylinder 24. The cylinder 31 has on its lower end a horizontal circumferential annular flange 32, designed to rest 30 on the upper surface of the flange 30. For securing the cylinders 24 and 31 together, I provide an internally screwthreaded ring, 33, having at its upper end an annular inwardly extending flange 34. The ring 33 is 35 designed to be set down over the flange 32, and to be screwed on to the flange 30. It will thus be seen that a space is left between the flange 29 and 32. To prevent rotation of the cylinder 31 and the ring 33, with relation to the cylinder 24, when the parts are 40 assembled, I provide a pin 35, which is received in the corresponding openings in the flange 34, the flange 32 and the flange 30. At its upper end, the cylinder 31 is provided 45 with laterally extending flanges 36, by which the carburetor is mounted on the engine.

In the upper end of the cylinder 31, is 50 mounted a butterfly or throttle valve 37, the stem 38 of which extends to position outside the cylinder 31. Fixed on the outer end of the stem 38 is a segmental plate 39 on which is formed a lever handle 40. By the movement of the lever handle 40, the throttle 55 valve 37 may be controlled.

For controlling the air inlet opening around the upper end of the gasoline inlet tube 25, I have provided the following mechanism: Extending upwardly from the flange 60 59 at regular intervals are pins 40. Pivoted

to each of the pins 40, is a flat curved metal plate 41. On the end of each plate 41, opposite the pivoted end thereof, and adjacent to the flange 30, when the plate is at the outward limit of its movement, is an upwardly 70 extending lug 42. The plates 41 are arranged so that part of each plate is above part of the next plate below as shown in Fig. 5. Above the plates 41, I place a flat disk 43 which is provided with a plurality 75 of slots 44 designed to receive the upwardly extending lugs 42. The slots 44 are elongated on radial lines of the plate 43 to permit sliding movement of the lugs 42 in said slots. At one side, the plate 43 is provided 80 with a horizontal extension 44 which is received in an elongated slot 45 in the flange 33. When the plates 41 are in their outward position, as shown in Fig. 5, the extension 44 is at the right hand end of the slot 45, as 85 said slot is shown in Fig. 6. When the extension 44 is moved to the left hand end of said slot, the lugs 42 slide inwardly in the slots 44 and the plates 41 reduce the area 90 of the central air inlet opening as shown by the dotted lines in Fig. 5. On the upper side of the extension 44 is fixed a block 46, the upper surface of which is approximately level with the upper side of the flange 34. Pivoted to the upper side of the block 46 is 95 a horizontal link 47. Fixed on the cylinder 31 is a bracket 48. Detachably and pivotally mounted at a point between its ends on the bracket 48 is a lever 49. Pivotally mounted on the plate 39 at a point spaced apart from 100 the longitudinal axis of the lever arm 40, is a rod 50. The rod 50 is pivotally and slidably mounted on one end of the lever 49 as shown in Fig. 1. On the other end of the lever 49 is detachably fixed a curved arm 105 51, and adjacent to the convex surface thereof, is a flat spring 52, one end of which is secured to the link 47. The spring 52, the arm 51 and the lever 49 are so arranged with relation to the link 47, that when the end of 110 the lever 49 to which the arm 51 is fixed is raised or lowered, the link 47 will be moved in such a manner as to rotate the plate 43 and thereby operate the plates 41 for opening the air inlet opening or closing it. By 115 means of the rod 50, the plates 41 and the throttle valve are operated in unison by means of the lever 40.

The rod 50 is mounted on the lever 49 in the following manner: On the lever 49 is 120 slidably mounted a block 53 which may be adjusted in any position of its movement by means of a set screw 54. Rotatably mounted on the block 53 is a collar 55 which is provided with an opening in which the rod 50 125 is slidably received. A set screw 56 may be used for fixing the collar 55 in any position of its movement on the rod 50.

By means of the mechanism just described, the relative movements of the throt- 130

tle valve and the plates 41 may be adjusted as desired and thereby the relative size of the air inlet opening and of the opening past the throttle valve, may be accurately adjusted.

For controlling the admission of gasolene from the tube 25 into the lower part of the cylinder 31, which forms a mixing chamber, by means of the lever 40, I have provided the following mechanism: A cross rod or brace 57 is mounted within the cylinder 31 above the upper end of the tube 25 in the following manner: In one side of the interior of the tube 31 is a recess 58 in which 15 one end of the rod 57 is received. In the opposite side of the tube 31 is a screw-threaded opening in which is received a screw plug 59, in the inner end of which is a recess which receives the other end of the 20 rod 57. In the rod 57 is a central vertical opening 60. A bell crank lever 61 is centrally pivoted at a point just above one edge of the slot 60 with one arm extending downwardly into said slot and with the 25 other arm extending horizontally above said slot. In the last mentioned arm of the bell crank lever 61 is an opening in which is received a valve stem 62. On the upper end of the valve stem 62 is a head 63 by which 30 said valve stem is prevented from sliding downwardly through the opening in said bell crank lever. On the lower end of the stem 62 is a valve 64 which coacts with the upper end of the tube 25. On the stem 62, just above the valve 64 is a ball 65 which 35 serves to scatter the gasolene vapor which is discharged into the mixing chamber from the tube 25. Mounted on the stem 62 between the ball 65 and the rod 57, is an extensible coil spring 66. In the end of the rod 57 adjacent to the downwardly extending arm of the bell crank lever 61, is a longitudinal opening which registers with an 40 opening in the tube 31. In the openings just described, is slidably mounted a rod 68, the inner end of which stands adjacent to the downwardly extending arm of the bell crank lever 61. Pivoted mounted on the outer side of the tube 31, above the outer 45 end of the rod 68, is a swinging lever 69. Centrally pivoted on the lower end of the lever 69, is a lever arm 70, the lower end of which is received in a slot 71 in the inner side of the bracket arm 48. Secured to the 50 inner side of the plate 39, near the point where the rod 50 is pivoted thereto, is a flat spring 72. The other end of the flat spring 72 is designed to normally rest adjacent to the opposite side of the inner surface of the 55 plate 39. Mounted in the plate 39 are screws 73 which extend from the outside to a point beyond the inner surface of said plate 39 and are designed to engage the side of the spring 72 which is adjacent to said 60 plate 39 thereby holding the free end of the 65

spring 72 away from the plate 39. Mounted in the upper end of the lever 70, is a roller 74 designed to engage and travel along the flat spring 72 when the lever 40 and the plate 39 are moved. It will be seen 70 that when the roller 74 travels from the fixed end toward the free end of the spring 72, the upper end of the lever 70 will be moved inwardly toward the tube 31. The outer end of the rod 68 stands in the path 75 of the lever 70 and is pushed inward when said lever is moved toward the tube 31. Mounted in the bracket arm 48 is a rod 75 on the inner end of which is a head 76, one side of which is convex and the other side 80 of which is flat. The head 76 is between the lower end of the lever 70 and the bracket arm 48 and the lower end of the lever 70 rests against said head. The position of the lower end of the arm 70 may be regulated 85 by turning the rod 75 to present either the flat side or the convex side of the head 76 to the lower end of the lever arm. Connected with the rod 76 by means of the universal joint, is a controlling rod 77 by means 90 of which the rod 75 and the head 76 may be operated.

In the practical operation of my improved carbureter, gasolene is drawn through the carbureter and is admitted through the tube 95 11 into the casing or receptacle 10. The weight of the float 18 raises the valve 12 and permits the intake of gasolene. When a certain predetermined liquid has accumulated within the casing 10, the float 18 is 100 raised and the valve 12 is seated by the action of the spring 20. Gasolene is fed from the casing 10 through the passage-way 26 to the tube 25. When the engine is started, the lever 40, as shown in Fig. 1 is moved to the 105 right, thereby opening the throttle, moving the plates 41 to increase the size of the air opening and unseating the valve 64 to admit gasolene into the mixing chamber. By means of the screws 73, the spring 72 may 110 be adjusted, thereby regulating the operation of the lever 70 and the valve 64. The operation of the valve 74 may also be regulated to some extent by means of the rod 75 and the head 76. By moving the block 53 115 longitudinally on the lever 49, and by moving the collar 55 longitudinally on the rod 50, considerable adjustment may be secured for controlling the movements of the throttle 37 and of the plates 41 with relation to 120 each other.

The advantages of my improved carbureter may be seen from the foregoing description. On account of the means whereby the air intake opening is controlled, by 125 the lever which operates the throttle, I am able to do away with the auxiliary air opening and the compensating valve which are used with many carbureters. By the means for adjustment hereinbefore described, I am 130

able to thoroughly and completely adjust the gasoline intake, the air intake, and the throttle valve with relation to each other.

It will, of course, be understood that the parts of my improved carbureter are so arranged that a sufficient quantity of air passes the upper end of the tube 25 at a sufficient velocity to draw more gasoline from the tube 25 than will be needed and that the valve 64 prevents flooding the carbureter. It is advisable in a carbureter of this kind that the flow of air past the upper end of the tube 25 should be so controlled and regulated at the nozzle and with reference to the needle valve as to produce as nearly as possible a uniform mixture. This advisable condition I am able to accomplish by regulating the size of the opening around the upper end of the tube 25 in unison with the movement of the throttle valve 37 and the needle valve. In view of the facts just mentioned it will be seen that the flow of gasoline is regulated by the valve 64 but the relative amount actually taken up by the air is regulated by the velocity of the air, the volume thereof and the course of travel of the air past the deflector ball 65.

I have found by a great many experiments that by controlling the size of the air opening immediately around the discharge end of the gasoline intake, usually called the nozzle, I am able to regulate quite accurately the mixture for keeping it uniform. This is especially true where the needle valve is regulated in unison with the iris valve. The carbureter may be adjusted so that when the engine is run at low speed the proper mixture is secured. Assuming this to be accomplished, then if the speed of the engine increases the suction through the carbureter is increased, thereby increasing the flow of air and carrying with it an increased amount of gasoline. It is usually true, however, when this happens, that the gasoline increases more than the proper amount in proportion to the increase in the air. This is true because with the usual carbureter the construction is such as to provide a greater vacuum than in my device. As will be seen in the drawing the air opening around the nozzle is of considerable size even when the iris valve is closed. The construction and regulation of my carbureter is such that the vacuum pressure is borne by the throttle and not by the air valve. With my device, the air flows comparatively freely around the nozzle at all times and therefore the variation in the speed of the engine, while it does increase the suction and therefore increases the supply of air and gasoline, does not increase the gasoline supply out of proportion.

Assuming the proper mixture of gasoline and air to be approximately 1 to 11, and assuming the throttle to remain in fixed position while the engine is run at low speed, and

assuming that the proper mixture is then secured, if the speed of the engine then increases and the construction of the carbureter is such that there is considerable vacuum at the nozzle, then both air and gasoline will increase but the proportionate increase of gasoline is too great.

With my device where the opening around the nozzle is comparatively large, a comparatively small degree of vacuum is created by increase in engine speed without throttle change and under such conditions the increased supply of gasoline and air occurs in approximately the proper fixed proportions. When it is desired to control the increase of fuel supply, the construction of my carbureter is such that when the throttle is opened, the air opening is enlarged and the needle valve is slightly raised and the uniformity of the mixture is thereby maintained. I have taken it to be a fact, however, that to regulate the flow of air and to control the inflow of gasoline by means of a valve alone is not sufficient to produce a perfect mixture which will be uniform at all times.

In order to effect a complete admixture of the gasoline and air and to complete the vaporization of the gasoline I have provided on the stem 62 the deflector ball 65. In this connection it may be noted that with a comparatively restricted opening around the upper end of the tube 25, and a comparatively small inflow of gasoline, the gasoline and air will properly mix. When, however, the valve 64 is raised and the opening around the upper end of the tube 25 is enlarged, the tendency would be for the gasoline to pass upwardly with the air, and in the absence of some deflector the mixture in the center of the tube 30 would be very rich and the gasoline would not be thoroughly vaporized, while the mixture around the outside of the tube 31 would be poor. That is to say in the center of the tube 31 there would be an excess of gasoline, and around the outside there would be very little gasoline. By means of the ball 65 the gasoline passing upwardly is deflected outwardly and driven toward the side walls of the tube 31 so that the gasoline is drawn into the upwardly passing current of air, and thoroughly mingled therewith. It will be seen that at all times a current of air and gasoline vapor strikes the lower portion of the ball 65, whereby the air and gasoline are formed into eddying currents by which a uniform mixture is created. Another advantage of the deflector is found in the fact that it enables me to secure a more delicate adjustment for producing a constantly uniform mixture. This is true because the increase in the size of the air opening around the nozzle and the opening of the needle valve, while it causes an increase in air supply and gasoline supply, does not maintain the

increase at exactly the proper proportion. So much of the air passes upwardly at a distance from the nozzle that not quite enough gasoline is supplied. I therefore provide 5 the deflector and the suction of the air around it tends to cause a slight vacuum immediately at the nozzle opening, thereby increasing the inflow of gasoline.

I claim as my invention:

- 10 1. In a carburetor, a shell having an air inlet opening and a discharge passage, a fuel feed nozzle extending into said shell to a point between said opening and passage and forming a valve seat at its discharge end, 15 an adjustable closure device surrounding said nozzle near its discharge end and adapted to vary the size of the opening in the shell around the nozzle, a needle valve arranged to coact with said seat, and provided with 20 an upwardly extending stem; a valve raising device slidably mounted on the said stem, a deflector device on said stem above said valve, and a yielding device arranged between said deflector and said valve raising 25 device.
2. In a carburetor, a shell having an air inlet opening and a discharge passage, a fuel feed nozzle extending into said shell to a point between said opening and passage and 30 forming a valve seat at its discharge end, an adjustable closure device surrounding said nozzle near its discharge end and adapted to vary the size of the opening in the shell around the nozzle, a needle valve arranged 35 to coact with said seat, and provided with an upwardly extending stem, a valve raising device on the said stem, slidably mounted, a deflector device on said stem above said valve, a yielding device arranged between 40 said deflector and said valve raising device, a throttle valve in said discharge passage, and means for simultaneously controlling said throttle valve, said closure device and said needle valve controlling means.
- 45 3. In a device of the class described, a carbureting chamber having a discharge outlet, a throttle valve in said discharge outlet,

a stem thereon extending outside said chamber, a fuel inlet tube extending into said chamber, the upper end of said tube forming 50 a valve seat, a valve arranged to coact with said seat, an upwardly extending stem thereon, a centrally pivoted bell crank lever having one end pivoted to said last named stem, a rod slidably mounted in the wall of said 55 chamber and designed in one position to engage the free end of said bell crank lever for opening said second valve, an arm centrally pivoted to the outer end of said rod, adjustable means for limiting the outward 60 movement of one end of said arm, means mounted on said throttle stem for engaging the other end of said arm and moving it inwardly when said throttle stem is moved to a certain position of its movement, and a 65 link pivoted to said chamber and to said arm for supporting it.

4. In a device of the class described a carbureting chamber having a discharge outlet, a throttle valve in said discharge outlet, 70 a fuel inlet tube extending into said chamber, the upper end of said tube forming a valve seat, the valve arranged to coact with said seat, a rod slidably mounted in the wall of said chamber and operatively connected 75 with said valve, said valve being arranged so that it is normally seated and is raised by the inward movement of said rod, an arm pivoted to the outside of said shell, and extending from position above to position below the outer end of said rod, means whereby said arm and said throttle valve may be operated in unison, and means whereby the limit of the outward movement of the lower end of said arm may be regulated, said 80 85 means comprising a rod rotatably mounted, and having a flat side adjacent to the lower end of said arm.
